(57) **CLAIM**

The ornamental design for the bottle, shown and described.

DESCRIPTION

FIG. 1 is a top, front perspective view of the new, and original and ornamental design for a bottle according to this invention;

FIG. 2 is a side elevation, rotated slightly counterclockwise from the bottle of FIG. 1;

FIG. 3 is a front elevational view of the bottle of FIG. 1; and, FIG. 4 is a top plan view of the bottle of FIG. 1.

The broken lines shown in the drawings are for environmental purposes only and form no part of the claimed design.
